UNITED STATES PATENT OFFICE.

HENRY A. KELLEY, OF KANSAS CITY, MISSOURI.

OIL-BURNER.

1,036,638.

Specification of Letters Patent. Patented Aug. 27, 1912.

Application filed March 1, 1912. Serial No. 680,911.

To all whom it may concern:

Be it known that I, HENRY A. KELLEY, a citizen of the United States, residing at Kansas City, in the county of Jackson and 5 State of Missouri, have invented certain new and useful Improvements in Oil-Burners, of which the following is a specification.

My invention has reference to a burner adapted for the use of liquid fuel, and my 10 objects are to provide a burner of this character wherein maximum efficiency is had with a minimum consumption of fuel; which can be readily disconnected or taken apart when desired, and which is not liable 15 to clog or become choked when in use.

In order that the invention may be fully understood, reference will now be made to the accompanying drawing, in which:

Figure 1 is a side elevation of my burner. 20 Fig. 2 is a front elevation of the burner. Fig. 3 is a vertical section on line III—III of Fig. 2. Fig. 4 is a horizontal section on line IV—IV of Fig. 3.

In carrying out the invention, I construct 25 the burner of three main parts, namely: a feed-chamber 1, a mixing-chamber 2, and a discharge-nozzle 3, which parts can be readily assembled or taken apart should it become necessary to clean said burner. Feed- 30 chamber 1 is of conical form and superimposed upon the mixing-chamber 2, it being divided therefrom by a removable partition 4 provided at its forward portion with a series of feed-tubes 5, depending into 35 the mixing-chamber 2 and provided at their rear lower portions with discharge orifices 6. The upper reduced portion of the feed-chamber 1 communicates with a supply-pipe 7, which conducts fuel oil thereto from a 40 suitable source, not shown. Mixing-chamber 2 is circular at its upper portion to receive the circular lower end of feed-chamber 1 and tapers downward and terminates at its forward end in a circular portion 8 provided 45 with coupling 9, whereby it is coupled to the rear circular portion of nozzle 3. Nozzle 3 flares forward and has an elongated discharge slot 10 at its forward end.

11 designates a plurality of vertical pins 50 extending through the nozzle 3 and arranged in rows to assist in atomizing the fuel as it passes through said nozzle.

12 designates a steam or other fluid supply-pipe leading from a supply source, not 55 shown, and extending into the rear portion

of the mixing-chamber 2, where it terminates in an elongated discharge-slot 13, approximately on a line with the lower terminals of the feed-tubes 5.

In practice, the fuel oil is supplied to the 60 feed-chamber 1 preferably under pressure and discharges therefrom through the feed-tubes 5 in the direction of nozzle 13, it becoming more or less heated in its passage through the feed-chamber and said feed-tubes. As the fuel oil discharges backward through the orifice 6, it impinges against the steam or other fluid under pressure discharged from the slot 13, which fluid commingles with and atomizes the fuel oil and 70 carries it forward through the mixing-chamber 2 and the nozzle 3, from which latter it is discharged in the form of spray or mist. As the mixture of fuel oil and fluid impinges against the pins 11 in its passage 75 through nozzle 3, said fuel oil is further atomized so that complete combustion results when the mixture discharges from slot 10 and becomes ignited.

While I have shown the preferred arrangement and construction of my burner, I do not wish to be confined to the specific arrangement disclosed, but reserve the right to make such changes as properly fall within the spirit and scope of the appended claim. 85

Having thus described my invention what I claim and desire to secure by Letters Patent, is:

A burner consisting of a feed-chamber, means for supplying said feed-chamber 90 with fuel oil, a mixing-chamber connected to said feed-chamber, a partition separating the feed-chamber from said mixing-chamber, feed-tubes depending from said partition into the mixing-chamber and provided 95 at their lower rear portions with discharge orifices, a discharge-nozzle communicating with the forward portion of the mixing-chamber, and a fluid supply-pipe projecting into the rear portion of the mixing-chamber 100 substantially on a plane with the lower terminals of the feed-tubes, for the purpose described.

In testimony whereof I affix my signature, in the presence of two witnesses.

HENRY A. KELLEY.
